UNITED STATES PATENT OFFICE.

MELVILLE D. JONES, OF BOSTON, MASSACHUSETTS.

DESIGN FOR IRON BRACKET.

Specification forming part of Design No. 5,635, dated March 5, 1872.

Specification describing a Design for Iron Brackets, invented by MELVILLE D. JONES, of Boston, in the county of Suffolk and State of Massachusetts.

The nature of my design is fully represented in the accompanying drawing to which reference is made.

That part of the bracket between the top, back, and front or scroll, consists of cross-bars, and at each crossing of the bars, are raised points; between the top and back of the bracket is a small scroll running across the cross-bars. The front of the bracket is a scroll running from the top near the end to the back

near the end, and ornamented with a line of raised points.

The distinguishing character of my design is the cross-bars and general outline of the scroll or front of the bracket.

What I claim as my invention is—

A design for iron brackets, in which cross-bars are used in connection with the scrolls, substantially in the manner above described.

MELVILLE D. JONES.
